AIRCRAFT SEAT

Robert Malitte, Paris, France
(Rue Jacques Riviere, Sceaux, Seine, France)

Filed May 7, 1963, Ser. No. 74,778

Term of patent 14 years

(Cl. D15—8)

FIGURE 1 is a top front perspective view of an aircraft seat embodying the design of the present invention, FIGURE 2 is a top rear perspective view of the unit, and

FIGURE 3 is an end view of the unit, showing the tray member in a position for use.

The end of the seat which is not shown is the same in appearance as the end which is shown.

I claim:

The ornamental design for an aircraft seat as shown and described.
